UNITED STATES PATENT OFFICE.

CHARLES S. KING, OF NEW ROCHELLE, NEW YORK.

DESIGN FOR FANCY TRIMMING.

41,711.

Specification for Design.

Patented Aug. 22, 1911.

Application filed May 16, 1911. Serial No. 627,641. Term of patent 3½ years.

To all whom it may concern:

Be it known that I, CHARLES S. KING, a citizen of the United States, residing in New Rochelle, in the county of Westchester and State of New York, have invented a new, original, and ornamental Design for Fancy Trimmings, of which the following is a specification, reference being had to the accompanying drawing, forming part thereof.

The figure is a face view of a portion of fancy trimming, showing my new design.

I claim:

The ornamental design for a fancy trimming, as shown.

CHARLES S. KING.

Witnesses:

T. F. BOURNE,
MARIE F. WAINRIGHT.
